CLAIM

The ornamental design for a cabinet handle, as shown and described.

DESCRIPTION

FIG. 1 is a perspective view of a cabinet handle shown independent of environment for ease of disclosure only;
FIG. 2 is a side elevation view thereof, shown independent of environment for ease of disclosure only;
FIG. 3 is a side elevation view thereof, shown independent of environment for ease of disclosure only;
FIG. 4 is top plan view thereof, shown independent of environment for ease of disclosure only; and,
FIG. 5 is a bottom plan view thereof, shown independent of environment for ease of disclosure only.

The broken lines shown represent unclaimed boundary lines and form no part of the claimed design.
